UNITED STATES PATENT OFFICE.

BENIAMINO ZENDRON AND GIUSEPPE ZENDRON, OF FARR, COLORADO.

PLAYING ATTACHMENT FOR ZITHERS AND OTHER STRINGED MUSICAL INSTRUMENTS.

984,176.

Specification of Letters Patent. Patented Feb. 14, 1911.

Application filed July 21, 1909. Serial No. 508,839.

To all whom it may concern:

Be it known that we, BENIAMINO ZENDRON and GIUSEPPE ZENDRON, subjects of the Emperor of Austria-Hungary, residing at Farr, county of Huerfano, State of Colorado, have invented certain new and useful Improvements in Playing Attachments for Zithers and other Stringed Musical Instruments, of which the following is a specification.

Our invention relates to improvements in playing attachments for zithers and similar stringed musical instruments, and the objects of our invention are,—first, to provide a key means of playing and operating the strings of a musical instrument known as a zither, or similar instruments; second, to provide means for applying the tremolo to the strings so played, when desired; third, to provide a means for playing such stringed instrument so as to have a wider range of expression; and fourth, to arrange the strings in combination with our device so that an accompaniment to the melody may be played. We attain these objects by the mechanisms illustrated in the accompanying drawings in which,—

Figure 1 is a perspective view of a zither with our attachment thereon shown in partly broken section; Fig. 2 is a vertical cross section view on line 2—2 of Fig. 1 showing the keys, tremolo attachment, and the relation to the strings of the instrument; Fig. 3 is a top plan view showing the keys and tremolo attachment; Fig. 4 is a cross sectional view longitudinally through the key board showing the detail of the pickers for the melody and harmony or accompaniment strings; Fig. 6 is a detail elevation showing the relation of the keys, the tremolo attachment and means for engaging and disengaging the same; Fig. 7 is a cross sectional view from the side showing the pickers in an extreme downward movement; Fig. 8 is a similar view showing the picker in the opposite position from the one shown in Fig. 7; Fig. 9 is a sectional side view showing the picking attachment; Fig. 10 is a perspective view partly in broken section showing the detail of the picking mechanism; Fig. 11 is a perspective view in broken section showing the means of engaging and disengaging the tremolo attachment; Fig. 12 is a perspective view in broken section showing the opposite end of the means of engaging and disengaging the tremolo attachment from that shown in Fig. 11; and Fig. 13 is a sectional detail

of the bridge at the head of the instrument showing the arrangement of the harmony or accompaniment strings. Fig. 14 is a front elevation of a fragment of the key-frame showing certain parts which coöperate with the picker fingers. 60

Similar numerals refer to similar parts throughout the several views.

The body of the instrument comprises a sounding board 1, sides 2, and a bottom 2^a. Two groups of strings are provided, said groups being denoted by the reference characters 13 and 8, respectively, in Fig. 1, the former being the melody strings, and the latter the harmony or accompaniment strings. At the head or upper end of the instrument is a bridge 9 and at the opposite end a bridge 7 for the strings. Across the last-mentioned end of the instrument extends a bar 7^a carrying pins 7^b for securing one end of the strings. The other ends of the strings are secured to tuning pins 9^a located adjacent to the bridge 9. 70

The strings of the group 13 range through the musical scale, and the strings of the group 8 are arranged in sets of three as indicated at 11 in Figs. 4 and 13, each of such sets of three strings being tuned to form a musical chord. The strings 11 are arranged 80 in rows perpendicular to the sounding board, and a little to one side of each row, and in the same horizontal plane as the lowermost string thereof, is located a single string 10 which is tuned to form the bass tone of the chord. 85 Each set of three strings is provided with a bass string. In order that the strings 10 and 11 may pass the bridge 9, the latter has openings through which the strings 10, and the two lowermost ones of the strings 11 90 pass, the upper one of said strings 11 extending across the top of the bridge as usual. 95 Fig. 13 clearly illustrates this arrangement. Fig. 13 clearly illustrates this arrangement.

At the tail of the instrument is attached a board 3 extending upward a suitable distance, and from the top of it extends a cover 12^a which connects with a key-frame 12, which latter is attached to the instrument in front of the bridge 7, and has its front portion closed with a suitable finishing board 105 arranged so as not to touch the strings.

The picking mechanism comprises the following devices: In the top of the key-frame 12 is an opening 14 extending perpendicularly to the strings and terminating in a shoulder 15 from which the opening is continued through the board to the bottom 110

thereof. The continuation 17 of the opening is angular for a purpose to be presently described. A stem 20 is loosely mounted in the opening 14, and has a portion 19 which is 5 angular in cross-section and extends through the part 17 of the opening, with a sliding fit. Rotation of the stem is prevented by the angular shape of the portion 19 and the part 17 in which it is mounted. The upper 10 end of the stem is provided with a key or button 21, below which the stem has shoulders 22 and 23. Between the shoulder 15 and the shoulder 23, a spring 16 is coiled around the stem. The lower end of the portion 15 17 of the stem is bifurcated, and between the two branches 24 thus formed is pivoted, as indicated at 25, a picker finger 26, the latter having a reduced portion 27 extending between the branches 24, through 20 which latter and the reduced portion of the picker finger, the pivot 25 passes. The opening 17, on the side farthest from the string to be picked, is formed with a pocket 18 in which is made fast, by a screw 25 or other suitable means 30, one end of a spring 29, the free end of which is in contact with the picker finger adjacent to its pivot 25. The lower end of the opening 17, on the same side as the pocket 18, is also enlarged on one side to leave space for the movement of the picker finger, and in the adjacent wall of the opening is a recess 32^a which extends to the bottom of the key-frame 12, and contains a block 32 spaced at 30 its upper end from the corresponding end of the recess. From one side of the finger 26 extends a pin 31 which works in the recess 32^a. The lower end or tip of the finger 26 is cut on a slant so as to extend at an oblique 40 angle to the string.

In operation, the spring 16 normally holds the picker finger 26 in elevated position by reason of its engagement with the shoulder 23 of the stem 20. In this position, the pin 31 is on that side of the block 32 which is nearest the string which the picker finger is to sound and the finger tip is opposite the string. Now, when the key 21 is pressed downwardly, the finger is moved perpendicularly to the string, and in the direction thereof, and the tip of the finger slides over the string and pushes it slightly to one side, the pin 31 in the meantime traveling downwardly in the recess 32^a, on the side of the block. When this pin reaches the lower end of the block the free end of the spring 29 engages the portion 27 of the finger above the pivot 25, so that when the pin clears the lower end of the block, the spring suddenly 50 swings the finger on its pivot away from the string, thereby causing the latter to sound. The pin is now in line with that portion of the recess 32^a which is on the other side of the block, so that when the key 21 60 is released, the finger rises, and the pin trav-

els upwardly along that side of the block. When the pin reaches the upper end of the block, the spring 29 engages the finger below its pivot, so that when the pin clears said upper end of the block, the finger swings 70 on its pivot in a direction to bring the pin in line with that portion of the recess 32^a which it occupied before the key was depressed. It will therefore be seen that the pin travels downwardly in the recess on one 75 side of the block and crosses the lower end thereof, and then travels upwardly in the recess on the other side of the block, and thence crosses the upper end thereof, and finally resumes its position on the first-mentioned side of the block at the upper end of the recess. 80

The harmony or accompaniment strings have three tips 11^a arranged so that all of the three strings will be picked practically 85 simultaneously, thus sounding the same together, and producing a musical chord.

A tremolo attachment is provided for the melody strings. This attachment comprises a block 4 which is pivoted at one of its lower 90 ends on a rod 5 extending across the instrument near the foot thereof, and mounted in suitable supports thereon. At the opposite upper end of the block is a horizontally extending finger 6, the extremity of which is 95 located beneath the shoulder 22. The lower portion of the block, at that end carrying the finger, is brought to a point 4^a so that it may come in contact with that portion of the string which is between the bridge 7 and 100 the pin 7^b. The relative position of the shoulder 22 and the finger 6 is such that the string is sounded before the shoulder engages the finger. A further depression of the key engages the shoulder with the finger, 105 whereupon the block swings downwardly and its point presses the string between the bridge 7 and the pin 7^b, and a continued rapid tremulous downward pressure on the key causes the string to be sounded 110 tremolo. It will be understood, of course, that each melody string is equipped with the herein-described tremolo attachment.

In order to throw the tremolo attachment out of action, there is provided a rod 39 115 which extends beneath the fingers 6. This rod is attached to one end of a bell-crank lever 34 having a handle 38, and pivoted at 35 to the side 2 of the instrument, the opposite end of the rod being connected to a link 120 34^a pivoted at 35^a to the other side of the instrument, as shown in Fig. 12. By means of this lever, the rod may be elevated sufficiently to engage the bottom of the fingers 6, as shown in Fig. 6, thus locking the block 125 and preventing its downward swing. Upon swinging the rod to the dotted position in Fig. 6, away from the fingers, the blocks are released, and the tremolo attachment may be actuated as already described. A cam 36, 130

pivoted at 37, to the side 2, is provided for locking the bell-crank lever.

We claim:

1. A keyed zither or other musical instrument having strings arranged in groups, the strings of the respective groups being tuned to form a chord when sounded simultaneously, picker fingers for said groups, said picker fingers having a plurality of tips to engage the respective strings of the groups to sound the same simultaneously, and actuating means for the fingers.

2. In a keyed zither or other musical instrument, the combination with a sounding board and strings, a portion of the strings being arranged in rows extending perpendicular to the sounding board; of picker fingers for the strings, the fingers of the rows of strings having a plurality of tips to engage the respective strings of the rows, to sound the same simultaneously, and means for actuating the fingers.

3. In a keyed zither or other musical instrument, the combination with a sounding board and strings, bridges over which the strings pass, and end fastenings for the strings; of picker fingers for the strings, means for actuating the fingers, said means including a shouldered sliding stem, and a tremolo device comprising members adapted to engage the strings between one of the bridges and the adjacent end fastenings, said members having a projection extending into the path of the shoulder of the sliding stem.

4. In a keyed zither or other musical instrument, the combination with a sounding board and strings, bridges over which the strings pass, and end fastenings for the strings; of picker fingers for the strings, means for actuating the fingers, said means including a shouldered sliding stem, and a tremolo device comprising members adapted to engage the strings between one of the bridges and the adjacent end fastenings, said members having a projection extending into the path of the shoulder of the sliding stem, and means for holding the members in inoperative position.

5. In a keyed zither or other musical instrument, the combination with a sounding board and strings, bridges over which the strings pass, and end fastenings for the strings; of picker fingers for the strings, means for actuating the fingers, said means including a shouldered sliding stem, and a tremolo device comprising pivoted members adapted to engage the strings between one of the bridges and the adjacent end fastenings, said members having a projection extending into the path of the shoulder of the sliding stem, a rod extending beneath the members for locking the same, and means for actuating the rod to release the members.
